UNITED STATES PATENT OFFICE.

MAX MATTHAEI, OF FRANKFORT-ON-THE-MAIN, GERMANY.

BUILT-UP IRON RAILWAY-SLEEPER.

1,143,415.

Specification of Letters Patent. Patented June 15, 1915.

Application filed November 29, 1913. Serial No. 803,765.

To all whom it may concern:

Be it known that I, MAX MATTHAEI, subject of the King of Prussia, residing at 27 Beethovenstrasse, Frankfort-on-the-Main, in 5 the German Empire, have invented certain new and useful Improvements in Built-Up Iron Railway-Sleepers, of which the following is a specification.

This invention relates to built-up iron rail- 10 way sleepers of the type in which the sleeper is hollow on its underside or saddle-shaped so as to straddle the ballast, in contradistinction to sleepers having a lower flat face which rests upon the ballast and supports 15 the sleeper, and my invention relates more particularly to saddle-shaped built-up sleepers of the type in which the sleeper comprises two supporting members of channel or similar section connected together by dis- 20 tance pieces.

Built-up saddle-shaped sleepers have been proposed comprising single or double angle irons spaced apart by top plates which, however, cover a considerable length of the space 25 between the angle irons and thus only a comparatively short section of the space between the angle irons can be filled with ballast from above. It has also been proposed to use two angle or channel irons with their 30 vertical webs opposed and kept apart by the chairs, but in this case, although the ballast might be filled into the space between the vertical webs from above, the horizontal flanges form the main bearing surface and 35 do not form a saddle-shaped bearing surface. Owing, however, to the close spacing of sleepers at the present day, it is very difficult to properly pack the ballast up from below to the inner bearing surface of saddle- 40 shaped sleepers, especially in the case of broad joint-sleepers and it is therefore the object of the present invention to provide a saddle-shaped sleeper which will readily enable the ballast to be filled in from above, so 45 that the construction of permanent ways and the work of ballasting can be carried out rapidly and still efficiently.

The improved sleeper not only embraces a larger amount of ballast to insure better 50 distribution of the load, but also enables sufficient ballast to be bedded both in front of and behind the sleeper as to give sufficient resistance against movement both in the direction of the track and toward the 55 sides, so that a displacement of the sleeper is almost entirely out of the question, but

nevertheless subsequent packing of the ballast for the purpose of adjusting the rail is possible. Besides this the object of the invention is to simplify the construction of 60 the whole system of sleepers and the connection between sleeper and rail. For this purpose the sleeper is built up of a number of parts, and consists in general of two supporting members connected by distance 65 pieces and spaced at such a distance from each other that the ballast can be filled from above into the space between the supporting members which are more or less of channel or similar section and are arranged with 70 their flanges oppositely disposed to one another. The lower part of the channel shaped supporting members of the sleeper is formed in such manner that there is a space between the members of substantially trapezoidal 75 or similar form open above for the greater part of its length. A sleeper is thus obtained of greater lower and upper breadth, of greater height and having a greater bearing-surface for the rails. Further, it is 80 possible to fill in the ballast from above through the broad space between the two supporting members and to thoroughly distribute and tamp it down, so that the sleeper rests firmly on the ballast and an unusually great amount of ballast is embraced 85 by the sleeper on both longitudinal sides of the same; the sleeper is thus able to an unusual degree to resist forces which tend to cause "creeping" on sections of the track 90 where the brake is applied, and to transmit 95 said forces to the ballast. Besides this the number of sleepers is considerably reduced while retaining the same distance between the supporting points of the rails from seat 95 to seat. It will therefore be seen that a 100 sleeper is obtained in which the bearing surfaces, and namely both the horizontal and saddle-shaped bearing surface is considerably increased and it is easily possible to adjust the height of the sleeper by raising it by means of a tamping pick and at the same time filling in ballast from above and packing the same tight. Thus a tightly packed 105 and inclosed bedding of ballast of prismatic form is obtained, the supporting capacity of which is further strengthened by the ballast packed up at the sides. It is further possible with this invention and without affecting the adjustability of the sleepers to fill in 110 with concrete the prismatically shaped space or chamber between the two supporting por-

tions of the sleeper, so that to a certain extent a sort of concrete under-sleeper is formed.

In the drawings various forms of the invention are shown by way of example.

Figure 1 shows in full lines a cross-section through one construction of the sleeper according to the invention, in which the rail is fixed by means of simple clamping plates. Fig. 2 shows a central longitudinal section through one half of a two-part sleeper according to the invention, said section being on the line G—H of Fig. 3. Fig. 3 is a plan view of one half of a portion of the track. Fig. 4 is a section on the line A—B, Fig. 5 is a section on the line C—D, and Fig. 6 is a section on the line E—F of Fig. 3. Figs. 7—10 show to a larger scale a special arrangement for firmly holding the rail on the sleeper by means of spring-hooks:— Figs. 7 and 8 showing the spring-hooks in two different positions, partly in section on the lines I—K of Figs. 9 and 10 respectively, and Figs. 9 and 10 showing central sections through the rail and spring-hook device, corresponding to Figs. 7 and 8. Figs. 11 and 12 represent in plan and section a gage-clamp of known type, while Figs. 13 and 14 show in side-elevation and in cross-section the arrangement of a rail-joint on a sleeper according to the invention. Fig. 15 shows in cross-section and Fig. 16 in longitudinal section on the line L—M of Fig. 15 a combined spring-hook and gage-clamp device. Fig. 17 is a longitudinal sectional view similar to Fig. 16 showing a modified form of combined spring-hook and gage-clamp device. Fig. 18 shows diagrammatically various examples of the supporting members of the multi-part sleeper according to the invention.

The sleeper consists substantially of the two channel-shaped supporting members 1, (Figs. 1—17) or similarly shaped supporting members (Fig. 18) whose webs 2 are placed facing each other, while their lower flanges 3 are inclined outwardly or curved (see Fig. 18), so that between the two supporting portions a space 4 of substantially trapezoidal, or similar shape is formed. The two supporting members 1 of the sleeper are held a proper distance apart by means of, preferably, four or five, short pieces of ordinary channel iron 5, and are held together by means of bolts 6 which at the same time pass through the channel irons 5. The webs of the channel irons 5 lie with their upper surfaces flush with the upper flanges of the supporting members 1. A plate 7 extends over the upper flanges of the supporting members 1 and the web of the channel irons 5, said plate having its ends 8 bent over the supporting members 1 and being attached to the channel iron 5 by means of a rivet 9 or the like.

The lower ends of the supporting members 1 of the sleeper can be formed either as shown by the full line 10 in Fig. 1, or extend vertically downwardly.

In order to render the use of special sole-plates unnecessary the two ends of the sleeper are arranged so as to have the usual cant of 1 in 20 as particularly shown in Fig. 2. In curves the outer ends of the sleepers are laid higher to give the necessary super-elevation. The joints of the rails can be arranged in the middle of the built-up sleeper and ordinary flat fish-plates can be employed.

In place of the ordinary clamping plates 13 (Fig. 1) gage-clamp plates 14 of known type are preferably used to allow of adjustment of gage of the rails 12, as shown in Figs. 2, 3 and 5 and especially in Figs. 11 and 12. These gage-clamps are of circular form and are each provided with an outwardly extending rib or flange 15. They are also each provided with an eccentric hole through which the bolt 16 passes, said bolt fixing the gage-clamp to the supporting member 1 of the built-up sleeper. The gage-clamp 14 is prevented from turning on the bolt 16 by means of a key 17. The foot of the rail is kept down by the flange 15, while the eccentric arrangement of the bolt allows of adjusting the gage of the rails in straight or curved sections by adjusting the gage-clamp 14 with the help of a tool engaging in the slots 14. The design of the gage-clamps enables the holes for the bolts 16 to be similarly arranged in all the sleeper parts and owing to the spring action of the spring-hooks 18 hereinafter described the gage can be adjusted without loosening the latter, i. e., without loosening the rails. The arrangement of the holes in the sleepers makes it necessary in curves to adjust the outer and inner rails at the same time in order to obtain the required gage; in the case of transition curves any required widening of the gage can be provided for. Four such gage-clamps are preferably employed for each attachment of the rails to the sleepers (see Fig. 3).

Special spring-hooks 18 serve to hold the rail on the built-up sleepers, these spring-hooks being shown in Figs. 2, 3, 5 and 6 and to a larger scale in Figs. 7—10. These spring-hooks 18 which are made of best quality steel lie between the two supporting members 1 of the sleeper and hold the foot of the rail on both sides. They are passed through the space between the supporting members 1 of the sleeper and are brought on to the foot of the rail by having their jaws sprung apart. For this purpose the upper portions of the spring-hooks are provided with holes 19 in order to allow of pins of any suitable tool being inserted therein to spring apart the jaws. After the spring-hooks have

been inserted in the space between the supporting members 1 of the sleeper the jaws are allowed to spring together so that the spring-hook then assumes substantially the position shown in Fig. 9. Thereupon a bolt 20 is passed through corresponding circular holes 21 in the webs of the supporting members 1. The bolt has the form shown particularly in Figs. 7-10, *i. e.*, it has a cylindrical part 24 adjacent its head 22 and a cylindrical part 25 adjacent its threaded end 23, but the middle portion of the bolt is elliptical. Moreover, its head 22 is, as shown in Figs. 7 and 8, of prismatic form and is provided with a slot 26 for the introduction of a spanner or key, and is also provided with a chamfer 27. After the bolt has been brought into the position shown in Fig. 7, but before it is drawn right through, it is turned through 90°, by means of a tool introduced in the slot 26, into the position shown in Fig. 8, so that the larger diameter of the central elliptical cross-section is vertical. The spring-hooks 18 are thereby subjected to a strain and press the rails firmly on to the supporting members 1. Hereupon the bolt is pushed right through, so that chamfer 27 of its head 22 rests against the inclined flange 3 of one of the supporting members 1 of the sleeper and then the nut 28 is tightened up.

If it is required to arrange a rail-joint on a sleeper according to this invention, a channel-iron 29 is fixed by means of bolts or rivets 30 in the space between the two supporting members 1 of the sleeper (see Figs. 13 and 14). The web of this channel iron is cut away with the exception of a portion equal to the breadth of the rail-foot, as shown in Fig. 14, so that the spring-hooks 18 grip the rail-foot and the rails can rest firmly on the supporting members 1 of the sleeper.

Anchoring-plates 31 (see Fig. 3) may be arranged laterally, in the usual manner to prevent displacement of the sleepers longitudinally, especially in curves.

Figs. 15 to 17 show two different forms of a combined gage widening and clamping device. The channel irons 5 fixed between the webs 2 of the supporting members 1 of the two-part sleeper have the form shown in Figs. 16 and 17, *i. e.*, the channel irons 5 are somewhat longer than those described above, and a portion is cut away from their webs at both ends so that the flanges project laterally beyond the web portion as shown at 31. The fastening of the rails is effected by means of spring steel clamps 32, which in the position shown in Figs. 16 and 17 grip above the rail foot and under the web 5 of the channel irons. In the form according to Figs. 15 and 16 the underneath side of one of the limbs of the steel clamps is provided with a nose-piece 33 which, as shown in the

cross-section Fig. 16, bears against the rail foot. The attachment of the steel spring-clamps to the channel iron 5 is effected by means of bolts 34, which pass through corresponding holes in the steel clamps 32 and web 5. The adjustment of the gage is carried out in this form of construction by shifting the channel iron 5. For this purpose slots are provided in the webs 2 of the supporting members 1 in the channel irons 5 or their projecting ends 31 through which either round or square bolts 35 pass. If the bolts 35 are circular in cross-section they are provided with a similar head to the head 22 of the bolts 20, as shown in Figs. 7 and 8.

In the construction shown in Figs. 15 and 16 there is a square bolt 35. The adjustment of the gage is effected by simply shifting the channel iron 5 together with the rail fixed upon it over the bolt 35. The gage required at any particular point is fixed by filling-in the slots in the flanges 31 and the webs 2 of the supporting members 1 with wedges 36, which are driven through toward the outside and which fix the position of the gage adjusting device. The wedges 36 may consist of simple iron strips which are bent over at both ends to keep them in position.

The construction shown in Fig. 17 is specially suitable when the steel clamps have only a small amount of spring action and less importance is attached to the tightening up of the bolts 34. In this case the steel clamps 32 are formed with hook-portions 37 which can be held together by means of bolts 38. Otherwise the arrangement of this combined gage widening and clamping device is the same as that of the construction according to Figs. 15 and 16. If it is desired to lessen the thickness of the upper broad flange of the supporting members 1 on which the rail rests, it is advisable to arrange strengthening iron straps 39 (Fig. 17) adjacent to the rail bearing surface, said straps having their ends bent over at the edges of the upper flange of the supporting members 1 as shown at 40.

By the adoption of the construction shown in Figs. 16 and 17 a smaller number of parts are required. Moreover, there is no longer any difference between the arrangement of the sleepers used under rail-joints and those used elsewhere. The attachment of the steel clamps 32 is easier to carry out than that of the hooks 18 in the other forms of construction. Moreover, the adjustment of the gage can be carried out without the bolts 34 having to be loosened.

Since the packing of the ballast between the supporting members 1 of the two-part sleepers is carried out by means of tamping it is possible in certain circumstances to make use of a much cheaper material for the ballast than the hitherto usually employed broken stone or shingle ballast. Moreover,

the whole design of the railway-sleeper according to the invention is adapted to allow of the rails being supported resiliently upon the sleepers by the introduction of suitable material between the rail and the sleeper.

Having now described my invention what I claim as new and desire to secure by Letters Patent is:—

1. A saddle-shaped built-up iron railway 10 sleeper comprising two supporting members of substantially channel section spaced apart and having their flanges oppositely disposed to one another, said members being of such shape as to form a space between them of 15 greater width at its lower part than at its upper part, and distance pieces connecting said members at such a distance from each other that ballast can be filled in from above into the said space.
2. A saddle-shaped built-up iron railway 20 sleeper comprising two channel-shaped supporting members each having an upper horizontal frame, a substantially vertical web and a lower outwardly and downwardly 25 directed flange, the flanges of the one member being oppositely disposed to the flanges of the other member and distance pieces connecting the said members at such a distance from each other that ballast can be 30 filled in from above into the said space.
3. A saddle-shaped built-up iron railway 35 sleeper comprising two channel-shaped supporting members each having an upper horizontal flange, a substantially vertical web and a lower outwardly and downwardly directed flange terminating in a horizontal portion, the flanges of the one member being oppositely disposed to the flanges of the other member and distance pieces connect-

ing the said members at such a distance from each other that ballast can be filled in from above into the said space.

4. A built-up iron railway-sleeper comprising two supporting members of substantially channel section having their webs disposed inwardly and facing each other, channel-shaped distance pieces intermediate said members and bolts passing through the webs of said members and through the flanges of said distance pieces to secure the same together.

5. In combination with a track-rail, a 45 sleeper comprising two channel-shaped supporting members, each having an upper horizontal flange, a lower inclined flange 50 and an intermediate web, the webs being disposed inwardly and facing each other, distance pieces between said members, and bolts 55 passing transversely through and rotatable in the webs of said members, each of said bolts having an enlarged head provided with a chamfer adapted to engage one of the inclined flanges.

6. In combination with a track rail, a 60 sleeper comprising two channel-shaped members having their webs disposed inwardly and facing each other, a channel iron between said webs, bolts passing through said webs and through the flanges of said channel iron through slots therein, and wedges 65 for securing said bolts in said slots.

In testimony whereof I affix my signature in presence of two witnesses.

MAX MATTHAEI.
